[57] CLAIM

The ornamental design for an aircraft nose and inlet, substantially as shown and described.

DESCRIPTION

FIG. 1 is a perspective view of an aircraft nose and inlet showing my new design;

FIG. 2 is an elevational view of the front of said aircraft nose and inlet;

FIG. 3 is an elevational view of one side of said aircraft nose and inlet, the elevational view of the other side being substantially a mirror image thereof;

FIG. 4 is a bottom plan view of said aircraft nose and inlet.

The broken line disclosure of a portion of an aircraft fuselage is for illustrative purposes only.
